UNITED STATES PATENT OFFICE.

ADOLPH BAUER, OF NEWARK, NEW JERSEY, ASSIGNOR TO RICHARD C. JENKINSON,
DOING BUSINESS AS R. C. JENKINSON & CO., OF NEWARK, NEW JERSEY.

COMBINED AIR PURIFIER OR HUMIDIFIER AND RADIATOR VENT VALVE.

Application filed March 20, 1924. Serial No. 700,497.

This invention relates in general to air purifiers and humidifiers and more particularly to such a device in which a purifying or perfuming liquid is vaporized by contact 5 with a circulating fluid such as steam or air.

The primary object of the invention is to provide a novel and improved combined 10 radiator vent valve and air purifier and humidifier which ensures quick and thorough venting of the air from a radiator, as is intended to be but not usually produced by the known radiator vent valves, to prevent the radiator from becoming air-bound and produce efficient heating of the radiator, 15 and at the same time utilize the vented air and steam to vaporize a purifying liquid to purify, disinfect and humidify the air of a room.

Another object is to provide such a device 20 including a novel and improved construction of casing for housing both an automatic radiator vent valve and an air purifier or humidifier, and means for varying the supply of steam or air to the air purifier and 25 humidifier without in any manner affecting the automatic operation of the vent valve.

Other objects are to provide a casing comprising two chambers having a common inlet for steam, one of which contains a vent 30 valve and the other of which contains absorbent material to receive a purifying or perfuming liquid to be vaporized by steam or air, and means in said casing for controlling the supply of steam or air to said 35 last-mentioned chamber independent of the flow of steam or air to said vent valve chamber; to provide a casing comprising a base and two concentric chambers one of which surrounds the other, said base having a common 40 steam inlet for one end of each of said chambers, the other end of the innermost of said chambers having a valved outlet controlled by an automatic valve means, and the corresponding end of the other chamber 45 being open to the atmosphere; to provide an air purifier or humidifier embodying novel and improved features of construction; to provide an air purifier or humidifier having an inlet for steam, an outlet for 50 said steam, an agitating fan mounted in said outlet, and means for directing a jet of steam to said agitating fan to drive the same for agitating the steam flowing from said outlet; to provide a combined radiator vent

valve and air purifier or humidifier, an agitator fan and novel and improved means for mounting said fan with respect to the outlet of said air purifier or humidifier and said valve, and means for directing a jet of steam to said fan for driving the same, and to obtain other results and advantages as may be brought out by the following description.

Referring to the accompanying drawings, in which the same characters of reference indicate corresponding and like parts,

Figure 1 is a transverse sectional view through a combined radiator vent valve and air purifier and humidifier embodying the invention;

Figure 2 is a horizontal sectional view taken on the line 2—2 of Fig. 1;

Figure 3 is a similar view taken on the line 3—3 of Fig. 1;

Figure 4 is a perspective view of one of the absorbent rings of the purifier or humidifier;

Figure 5 is a similar view of one of the wire spacing rings;

Figure 6 is a fragmentary sectional view of the top of the casing showing a modification of the invention, and

Figure 7 is a horizontal section taken on the line 7—7 of Fig. 6.

In the specific embodiment of the invention shown on the drawings, the reference character 1 designates the base of the casing of the device which is formed with a recess 2 in its top side. An exteriorly threaded nipple 3 projects laterally from the base to fit into the usual opening 4 of a radiator R, the passage of said nipple communicating with said recess 2. A tubular casing 5 has a threaded connection with the base 1 within the open end of the recess 2, said casing communicating at one end with the recess 2 and being closed at its other end except for a vent opening 6 with which cooperates a needle valve rod 7 carried by a piston float 8. The said piston float is mounted within the casing and maintained in alinement with the vent opening 6 by means of spiders 9 and 10 secured within the casing 5 adjacent the ends thereof and through openings in which the needle valve rod 7 is adapted to slide. The piston float 8 is so constructed that it will be actuated upwardly by a predetermined pressure of air or steam in the radiator to which the device is applied to

close the vent opening 6, the float being also adapted to be raised to close the vent opening 6 by an influx of water to the casing.

A second tubular casing 11 has a threaded connection at one end with the base 1 exteriorly thereof, said casing being substantially coaxial with the casing 5 and surrounding the latter in spaced relation. A plurality of rings 12 formed of suitable absorbent material, such as asbestos, are arranged in superposed spaced relation in the casing 11, certain of said rings having their outer edges in contact with the walls of the casing 11 and their inner edges spaced from the walls of the casing 5, while the other rings have their inner edges in contact with the walls of the casing 5 and their outer edges spaced from the walls of the casing 11. The said rings are preferably maintained in spaced relation by means of wire rings 13 which are corrugated or otherwise formed to provide passages between themselves and adjacent rings 12. A comparatively hard or non-absorbent ring 14 is interposed between the casings 5 and 11 above the uppermost ring 12 so as to close the space between the said casings 5 and 11. The said ring 14 is formed with a plurality of transverse openings 15 between the center and the periphery thereof. The upper end of the casing 11 is preferably provided with a cover 16 which may be perforated or provided with wire screen.

A passage 17 is provided in the wall of the base 1 and controlled by a suitable valve such as the screw needle valve 18 cooperating with a seat 19 in the passage 17. A second passage 20 is provided in the base 1 and communicates at its upper end with the space between the casings 5 and 11 and at its lower end with the valve seat 19. The valve 18 is provided with a by-pass groove 21 whereby a limited communication between the recess 2 and the passage 20 is always provided.

In the operation of the device, the casing is secured to a radiator or the like by means of the nipple 3. Upon entrance of steam into the radiator the air is ejected therefrom into the recess 2 of the combined valve and air purifier and humidifier. The air will escape both from the vent opening 6 and through the by-pass 21 of the valve 18 and passage 20 into the space between the casings 5 and 11. The air flowing through the passage 20 will pass upwardly in a tortuous path between the rings 12, through the openings 15 and perforated cover 16 into the air of the room. When steam enters the recess 2, the valve 7 will be actuated to close the vent 6. However, steam will continue to flow through the by-pass 21 and passage 20 upwardly between the rings 12 and into the air of the room, whereby the air is moistened or humidified. The amount

of steam flowing through the passage 20 and the degree of humidity of the air of the room may be regulated by the valve 18. Due to the constant flow of steam through the by-pass 21, it will be observed that the radiator will be prevented from becoming air-bound, thereby providing for efficient heating of the radiator, this venting of the steam and air through the by-pass 21 taking place even though the vent valve 7 should become inoperative or clogged. It will also be noted that the regulation of the amount of steam passing between the rings 12 is independent of the steam or air actuating the vent valve. The openings 15 divide the steam into a plurality of fine jets so that the same is thoroughly distributed into the atmosphere. Should water flow into the device it will be absorbed by the rings 12, and upon passage of steam and air through the chamber between the casings 5 and 11 this water will be evaporated and carried into the atmosphere.

Where it is desired to purify, disinfect, medicate or perfume the air of a room, the rings 12 are saturated with a purifying, medicating or perfuming liquid, such as oil of eucalyptus. The air and steam passing through the passages 17 and 20 will vaporize the said liquid in the rings 12 and carry the same into the atmosphere.

In some cases, for instance where the device is placed on the radiator near the floor, it may be desirable to provide means for mixing the vapors and to thoroughly distribute the same into the air of the room. For this purpose, I may form the upper end of the casing 5 with a boss 22 and journal an agitating or mixing fan 23 of any suitable construction thereon, as shown by Figures 6 and 7, the blades of said fan being inclined to the plane of its rotation. The steam or air ejected from the openings 15 beneath the fan 23 will strike the blades and rotate the fan in the usual manner to produce a circulation of the air and raise the vapors upwardly and thoroughly distribute the same. In this connection it will be noted that the chamber formed by the casings 5 and 11 and the ring 14 serves as a collector or storage chamber for the steam or air, the pressure in which is constantly supplemented by the incoming air or steam from the radiator. The openings 15 divide this air or steam into small jets under a sufficient pressure to effectively drive the fan 23.

While I have shown and described the casing of the device as embodying certain details of construction, it will be understood that many changes and modifications can be made in these details without departing from the spirit or scope of the invention. Also, while I have shown the device for use in connection with radiators of steam heating systems, it will be understood that the de-

vice is equally well adapted for other uses where a circulation of a fluid such as air or steam is present. Therefore, I do not desire to be understood as limiting myself except as required by the following claims when construed in the light of the prior art.

Having thus described the invention, what I claim is:

1. A device of the character described, comprising a casing having two chambers communicating with a common fluid inlet and having independent outlets, a valve in one of said chambers which operates to automatically close its said outlet in response to a predetermined fluid condition within said chamber, and an absorbent material in the other of said chambers between its said outlet and said inlet.

2. A device of the character described, comprising a casing having two chambers communicating with a common fluid inlet and having independent outlets, a valve in one of said chambers which operates to automatically close its said outlet in response to a predetermined fluid condition within said chamber, an absorbent material in the other of said chambers between its said outlet and said inlet, and means for regulating communication between said inlet and said second-mentioned chamber.

3. A device of the character described, comprising a casing having two chambers one of which surrounds the other, said chambers communicating at one end with a common fluid inlet and having independent outlets at their other ends, an automatic valve for controlling the outlet of one of said chambers, and an absorbent material in the other of said chambers between said inlet and the outlet of said last-mentioned chamber.

4. A device of the character described, comprising a casing including a base having a fluid inlet, two casings secured to said base one of which surrounds the other in spaced relation and each of which communicates at one end with said inlet, said casings having independent outlets, an automatic valve in the innermost of said casings to control the outlet thereof, an absorbent material within the outer one of said casings between said inlet and the outlet thereof, and valve means for regulating the communication between said inlet and said last-mentioned member.

5. A device of the character described, comprising a casing including a base having a recess in one side thereof and a fluid inlet communicating with said recess, a casing secured at one end to said base communicating with said recess and having an outlet, an automatic valve in said casing to control said outlet, a second casing secured to said base and having an outlet, a passage in said base between said recess and said second-mentioned casing whereby fluid may flow from said recess into said second-mentioned cas-

ing, and an absorbent material in said second-mentioned chamber between said passage and said outlet thereof.

6. A device of the character described, comprising a casing including a base having a recess in one side thereof and a fluid inlet communicating with said recess, a casing secured at one end to said base communicating with said recess and having an outlet, an automatic valve in said casing to control said outlet, a second casing secured to said base and having an outlet, a passage in said base between said recess and said second-mentioned casing whereby fluid may flow from said recess into said second-mentioned casing, an absorbent material in said second-mentioned chamber between said passage and said outlet thereof, and a valve in said passage for controlling flow of fluid therethrough.

7. An air purifier or humidifier comprising a casing having a fluid inlet and an outlet, a plurality of spacedly superposed absorbent members therein between said inlet and said outlet to permit flow of fluid therebetween from said inlet to said outlet, and a corrugated wire ring between each two adjacent ones of said members to maintain said members in spaced relation to each other.

8. A device of the character described, comprising a casing including a base having a fluid inlet, two casings secured to said base one of which surrounds the other in spaced relation and each of which communicates at one end with said inlet, said casings having independent outlets, an automatic valve in the innermost of said casings to control the outlet thereof, a plurality of spacedly superposed absorbent rings in the outer one of said casings between the inlet and the outlet thereof and surrounding said innermost casing, the inner peripheries of certain of said rings being in contact with the walls of the said inner casing and the outer peripheries being spaced from the walls of the outer casing, and the others of said rings being alternately arranged with respect to said first-mentioned rings and having their inner peripheries spaced from the walls of the inner casing and their outer peripheries in contact with the walls of the outer casing to permit fluid to flow from said inlet in a tortuous path between said rings.

9. The device set forth in claim 1 with the addition of a mixing fan arranged adjacent the outlet of the second-mentioned chamber and driven by the fluid discharged therefrom.

10. The device set forth in claim 3 with the addition of a mixing fan journaled upon the outlet end of the inner of said chambers to be driven by fluid discharged from the outlet of the outer chamber.

11. A device of the character described

4 comprising a casing having a chamber provided with an outlet and with an inlet to be connected to a source of fluid under pressure, an absorbent material arranged within said chamber between said inlet and said outlet to permit fluid to flow into contact therewith and from said inlet to said outlet, and a mixing fan journaled upon said casing off center from and above said outlet, the blades of the fan being inclined to 10 the plane of rotation of the fan so as to be driven by fluid discharged from said outlet.

ADOLPH BAUER.
